VAPOR WASHING APPARATUS

Edward A. Pirsh, Westport, Conn., and Edwin J. Wagner, Jr., Washington, D. C., assignors to The Babcock & Wilcox Company, New York, N. Y., a corporation of New Jersey

Application October 19, 1955, Serial No. 541,431

2 Claims. (Cl. 261—98)

This invention relates to apparatus for purifying high pressure steam, and more particularly to washing apparatus for removing silica vapor from the high pressure steam produced in a vapor generator.

It is known that high pressure steam usually contains solid impurities that are either in the vapor state or mechanically entrained in the vapor as minute particles of solids. These impurities pass with the steam from the vapor generator and the impurities are usually subsequently released when the vapor is cooled during subsequent use in, for example, expansion engines. The impurities frequently cause difficulties from deposition in superheater tubes or in other tubular conduits leading to the expansion engine. When the expansion engine is of the turbine type the impurities are deposited on the surfaces of the turbine, resulting in a gradual loss of turbine efficiency and capacity.

Heretofore mechanical means had been used with success in the removal of the mechanically entrained impurities in the steam. Such means have taken the form of cyclone separators, tortuous path separators, and the like. However, when the steam is generated at high pressures, as is common today, the mechanical removal of the entrained solids does not effectively remove the vaporized impurities, such as silica and siliceous compounds, which are present in the steam delivered by the vapor generator.

It is known that silica vapors can be removed from high pressure steam by washing the steam with a relatively pure wash water. Apparently the wash water contacting the steam absorbs the silica vapors and the absorbed silica can be removed from the steam with the wash water. The effectiveness of the wash water removal of the impurities is largely dependent upon the intimacy of contact between the steam and the wash water, and the effective removal of the wash water from the steam flow path after washing contact with the steam.

In the present invention, wash water is atomized, i. e., dispersed into droplets, by the action of flowing streams of high velocity steam through the wash water. This is accomplished by providing spaced perforated trays in the flow path of the steam moving through a steam and water drum toward the steam outlet thereof. In such devices the effective contact between wash water and the steam can only be attained through a relatively narrow range of steam volumetric flows through the washing device. In accordance with this invention we provide a mass of woven metallic mesh material which is positioned between the vertically spaced perforated trays. In operation the upper tray is supplied with wash water and serves as a distributing means for the downward flow of wash water through the perforations of the tray. The water moving downwardly through the washing device contacts the mass of woven wire material with the water adhering to the surfaces of the mass so as to afford an extensive surface for contact between the downwardly moving wash water and the upwardly moving steam.

2

The wash water draining from the mass of woven wire cloth deposits upon a lower perforated tray where it is again atomized and contacted by the ascending streams of steam. The perforated lower tray not only adds to the overall efficiency of steam and wash water contact, but also serves as a distributor for the steam entering the washer.

While the effective operation of the perforated trays, insofar as silica removal is concerned, is limited between a definite dispersion point and a flood point where the upper and lower limits are determined by the steam velocity through the perforations and the amount of wash water used, the mass of wire mesh is not so limited and is capable of creating silica absorptive conditions between the wash water and the steam through a greatly increased range of steam flow conditions.

The various features of novelty which characterize our invention are pointed out with particularity in the claims annexed to and forming a part of this specification. For a better understanding of the invention, its operating advantages and specific objects attained by its use, reference should be had to the accompanying drawings and descriptive matter in which we have illustrated and described a preferred embodiment of the invention.

25 Of the drawings:

Fig. 1 is a sectional part elevation of a steam and water drum containing the steam washing apparatus of the present invention; and

Fig. 2 is an enlarged perspective view, of a portion of 30 the steam washing apparatus shown in Fig. 1.

As shown in the drawings, the steam and water drum 10 of a steam generator is provided with a plurality of riser tubes (not shown) which discharge a mixture of steam and water into the drum. Ordinarily the riser tubes 35 are positioned to discharge into the lower segment of the drum. A steam outlet 11 consisting of a row of tubular connections is positioned in the upper portion of the drum for the discharge of saturated steam to the customary superheater headers of the vapor generating and superheating unit. The drum 10 is provided with suitable downcomer connections (not shown) at the opposite ends thereof for the downward movement of water into the circulatory system of the steam generator. In the embodiment of the invention shown the steam and water mixture entering the drum 10 through the riser tubes 40 is passed through a plurality of steam and water separators 12 with the water discharging from the separators into the water space 13 in the lower portion of the drum 10 and the steam passing upwardly from the separators 12 into the steam space in the upper portion of the drum.

The drum 10 is provided with structural members spaced from the inner surface of the drum to provide a chamber 15 which collects the steam and water mixture 55 discharged by the riser tubes for the distribution of the mixture into tangential inlet ducts 16 individually connected to each of the steam and water separators. The separators 12 disclosed in the drawings are of the cyclone type and are described and claimed, for example, in U. S. Patent 2,368,211. As shown, the separators are arranged in rows for parallel flow of steam from the chamber 15 and are each provided with a corrugated plate scrubber 17 upwardly adjacent the upper steam outlet 18 from the separator. With the construction 60 described substantially dry steam is discharged from the upper outlet portion of the steam separators 12 and is passed in an upward direction toward the steam outlet 11.

The steam purifying unit 20 of the invention is disposed 70 within the steam drum downwardly adjacent the steam outlet 11, and is positioned in the steam space 14 of the

drum 10. The unit includes depending plates 21 attached at their upper ends to the drum 10 and forming a closed structure open at its lower end in communication with the steam space 14 and enclosing the lower end of the outlet 11.

As shown, structure 22 of inverted V shaped section is positioned beneath the lower end of the steam purifying unit 20 so that the steam entering the unit must pass between the lower edge portions of the depending plates 21 and the upper surface of the baffle 22. The baffle also serves to receive the downward flow of wash water discharging from the steam purifying unit 20, and returns that water to the water space 13 of the drum with a minimum of agitation of the water surface. This baffle structure arrangement effectively avoids the entrainment of drum water in the steam passing into the steam purifying unit.

The steam purifier unit 20 is provided with a pair of horizontally disposed vertically spaced upper and lower perforated trays 23 and 24, respectively. In a preferred arrangement of the unit, the trays 23 and 24 are vertically spaced approximately 6" apart for effective use of the device with each of the trays formed of a metallic plate which is punched or otherwise perforated with a plurality of circular openings which have an aggregate area of approximately 33 percent of the total area of each tray. The perforations are of the order of $\frac{3}{16}$ " in diameter and are arranged in a triangular spacing of approximately $\frac{5}{16}$ ", center to center of the perforations.

In accordance with the present invention a mass 25 of woven wire cloth is inserted in the space between the upper and lower trays. The woven wire cloth is formed from light gage stainless steel wire, of for example .011 inch diameter, which is loosely woven together to form a mesh which may be compacted into a mass having a density of approximately 12 pounds per cubic foot. As shown in a preferred embodiment in Figs. 1 and 2, the mass of wire mesh is approximately 3" in depth and is installed in the intertray space so that the upper edge surface 26 of the mass 25 is approximately 1" below the upper tray 23 and having its lower surface 27 approximately 2" above the upper surface of the lower tray 24.

Means are provided for the delivery of relatively pure wash water to the upper tray 23. The wash water may originate in the feed water for the boiler, or may originate in a separate supply of distilled water of high purity. The wash water is delivered at a controlled rate through a supply pipe 28 which is provided with a plurality of branch pipes 30 which terminate upwardly adjacent the upper tray 23 and substantially in vertical alignment with the centerline of the tray. Each of the branch pipes 30 is provided with a spray nozzle head 31 which is constructed and arranged to project the wash water downwardly in a multiplicity of streams distributed across the cross sectional area of the steam purifying unit 20. As shown in Fig. 1, the pipe 28 is extended through a drum inlet nozzle 32, so as to avoid thermal shock to the wall of the drum 10.

In assembling the washing unit 20 the plates 21 are supported from the drum, and the trays 23 and 24 are attached to the plates by through bolts 33. The mass of wire mesh material is positioned by a plurality of stainless steel strips $3\frac{1}{8}$ " x 1" in section extending across the unit and attached to angle members on the plates 21. The strips are disposed on edge and occupy less than 10% of the cross sectional area of the unit 20. A corrugated plate scrubber 35 is spaced above the tray 23, in the path of steam flow, immediately below the perforated distributor or dry pan 36 adjacent the steam outlets 11. The corrugated plate scrubber and the dry pipe are utilized to remove droplets of moisture entrained in the steam passing toward the steam outlet 11. The scrubber 35 is directly mounted between and supported from the plates 21.

In the operation of the steam purifying unit 20 the

wash water is supplied to the upper tray 23 in a quantity substantially equivalent to, for example, 10 percent of the total boiler feed water. The wash water will gravitate downwardly through the perforations of the tray 23 and will fall upon the mass 25 of woven wire immediately below the tray and will be substantially completely distributed across the entire cross sectional area of the mass 25. The water flowing down through the mass of wire mesh will be deposited upon the lower tray 24, from which the water passes through the perforations thereof to discharge downwardly under the influence of gravity onto the baffle 22 positioned below the steam purifying unit 20. The wash water thereafter joins the water in the water space 13 of the drum and, mingling therewith is conducted through downcomers into the circulatory system of the steam generator.

With the wash water flowing through the steam purifying unit in a downward direction under the influence of gravity, the steam passing into the opening between the depending plates 21 and the baffle 22 will move upwardly toward the steam outlet 11. The relationship between the total volume of steam passing upwardly through the steam purifying unit and the total area of the perforations in the tray determines the degree of mixing between the steam and the wash water. As the volume of steam increases in the rate of its flow through the apparatus the steam velocity through the perforations increases until the velocity of the ascending steam leads to an atomization of the wash water on the trays. This relationship between the velocity of the steam and its effect upon the wash water is known as the dispersion point.

When the dispersion point is reached the wash water is atomized into a mist of water droplets which is in intimate contact with the ascending streams of steam. This intimate contact leads to an effective exchange between the wash water and, for example, silica vapor included in the steam. At the dispersion point the mist of wash water, created by the velocity of the steam passing through the perforations, will rise within the space between the tray 24 and the lower surface of the mass 25 of woven wire mesh, with the mist separating from the steam, and returning to the tray for reatomization by the steam.

After the steam has reached a velocity condition which results in the atomization of the wash water any increase in the steam velocity will increase the agitation of the wash water above the tray until the mass of finely divided wash water and steam rises to the lower surface of the mass of woven wire mesh. When this condition occurs water will tend to be carried over by the steam into the mass 25 of woven wire. This condition leads to a loss of efficiency in the separation of the entrained solids and silica vapor from the steam, and is known as the flood point of the unit's operation. The flood point can also be reached by an increase in the rate of wash water delivery to the tray 23.

After the steam has been intimately mixed with the wash water, as described, the steam ascends through the mass 25 of woven wire mesh where it is in intimate contact with the descending wash water. Thereafter the steam ascends through the upper tray 23 where the atomization of the wash water described on the lower tray 24 is repeated. Thus, in the apparatus described the steam is subjected to two stages of intimate contact with wash water by reason of the atomization of the wash water, with an intermediate stage where the steam is in contact with small wash water particles in the mass 25 of wire mesh. It is believed that the water passed down through the wire mesh tends to follow a path generally along the point of contact between adjacent wires where such wires cross at an angle to each other. Due to the small size of the wire used in the mass 25 the water particles, or droplets, moving downwardly through the mass is finely divided and provides an intimate contact between the wash water and the steam.

Whereas the effective contact between wash water and

steam in the area immediately above the perforated tray is substantially reduced when the steam flow through the perforations is below the dispersion point, the wire mesh mass 25 maintains the effective contact between wash water and steam through a much wider range of steam flow through the steam purifying unit.

In an actual installation utilizing high pressure steam and boiler feed water, the described steam washing unit was found to be capable of removing significant quantities of silica from the steam over a relatively wide range of steam flow rates. For example, at a steam flow rate of 12,000 to 13,000 pounds of steam per hour per square foot of washing unit area, and a wash water flow rate of approximately 7.5% of the steam flow rate, the silica removal approximated 82%. At a 6,000 pound per hour per square foot steam flow rate, i. e., at approximately $\frac{1}{2}$ steam flow, and a water flow rate of approximately 16% of the steam flow, the silica removal from the steam was approximately 74%. With the mass 25 of wire mesh material removed from the steam washing unit, and a third perforated tray substituted therefore, the silica removal from the steam approximated 72% at full steam flow rating (with substantially the same steam and wash water flow rates as given in the example), while at $\frac{1}{2}$ steam flow (water flow rates substantially the same as in the example) the silica removal approximated 50%. Under both arrangements, i. e., with and without the insertion of the mass 25, the flood point or upper steam flow rate approximated 14,000 pounds of steam per hour per square foot of unit 20 cross-sectional area with a wash water flow rate of 400 pounds per hour.

While the use of a greater thickness of wire mesh material in a unit 20 of the same or similar overall height increased the silica absorption efficiency of the steam washer, the flood point or steam washing capacity of the unit was drastically reduced.

While in accordance with the provisions of the patent statutes the applicants have illustrated and described the most efficient embodiment of their invention now known, it will be understood that changes in the relative spacing of the component parts of their steam washing apparatus may be used and some parts may be used alone or in combination without departing from the concept of the invention.

What is claimed is:

1. The combination with a steam and water drum

having a steam outlet in the upper portion thereof and means for introducing a steam and water mixture to said drum, of a steam washer positioned in the upper portion of said drum and interposed in the steam flow path to said outlet comprising horizontally disposed vertically spaced upper and lower perforated trays, a mass of woven wire mesh positioned between said perforated trays and having the upper and lower portions of said mass of woven wire mesh spaced from the adjacent surfaces of said trays, said lower tray being vertically spaced from the lower surface of said mass of woven wire mesh, and means for delivering wash water to the uppermost of said trays for downward flow of wash water through said steam washer countercurrent to the ascending stream of steam.

2. The combination with a steam and water drum having a steam outlet in the upper portion thereof and means for introducing a steam and water mixture to said drum, of a steam washer positioned in the upper portion of said drum and interposed in the steam flow path to said outlet comprising horizontally disposed vertically spaced upper and lower perforated trays, a mass of woven wire mesh positioned between said perforated trays and having the upper and lower portions of said mass of woven wire mesh spaced from the adjacent surfaces of said trays, said lower tray being spaced from the lower surface of said woven wire mesh an amount less than the thickness of the mass of woven wire mesh, and means for delivering wash water to the uppermost of said trays for downward flow of wash water through said steam washer countercurrent to the ascending stream of steam.
